UNITED STATES PATENT OFFICE.

URIAH D. MINER, OF STARKE, FLORIDA.

WATCH-MAKER'S PUNCH.

SPECIFICATION forming part of Letters Patent No. 450,520, dated April 14, 1891.

Application filed December 13, 1890. Serial No. 374,603. (No model.)

To all whom it may concern:

Be it known that I, URIAH D. MINER, a citizen of the United States, residing at Starke, in the county of Bradford and State of Florida, 5 have invented certain new and useful Improvements in Watch-Makers' Punches; and I do hereby declare the following to be a full, clear, and exact description of the invention, such as will enable others skilled in the art to 10 to which it appertains to make and use the same.

My invention consists in a new and improved watch-maker's punch and stamp, which will be hereinafter fully described and claimed.

15 Referring to the accompanying drawings, Figure 1 is a side view of my new and improved jeweler's punch, showing the same closed, and in dotted lines showing it open. Fig. 2 is a central longitudinal sectional view. 20 Fig. 3 is a detail view of the adjustable steel disk; and Fig. 4 is a detail view, which will be hereinafter described.

The same numerals of reference indicate corresponding parts in all the figures.

25 Referring to the several parts by their designating-numerals, the upper jaw 1, the lower jaw 2, and the lower handle 3 are all cast or formed integral in one piece. The end of the upper jaw 1 is formed with a vertical opening 4, in which the punch 5 works. A spiral spring 6 encircles the stem of the punch at the point shown, and tends to raise it when it is relieved from the pressure of the operating-lever. The upper end of the punch-stem 30 is formed with a longitudinal slot 7, through which passes the curved outer end of a centrally-pivoted lever 8, the slotted inner end of which has an anti-friction roller 9, journaled transversely in it, as shown. The upper handle 10 is pivoted in the body 1^a of the tool at the point shown, and is formed with the upwardly-curved forward end 11, which passes through the slotted inner end of the lever 8, under the roller 9. It will be seen that 40 45 50 55 60 65 70 75 80 85 90 95 100

The lower jaw 2 has the openings 12 13 formed in it, and in the opening 13 is seated the pivot-stem 14 of the adjustable steel disk 15. This disk is formed with a milled edge for convenience in turning it with the fingers, 55 and is formed with a series of different-sized openings 16, arranged around the disk, as shown. These openings are formed in the disk so that as the latter is turned they will each in turn register with the upper end of the opening 12 in the lower jaw. By this means the piece of metal or broken pivot punched from the watch-wheel or metal plate placed upon the disk 15 will fall down through the opening 12 and be thus disposed of. To hold 65 the disk 15 rigidly at the point to which it is turned a clamping-bolt 17 is seated in a transverse opening in the lower jaw, and has a handle 18 on its outer end, by which it can be turned to cause the inner end to bear against 70 the pivot-stem 14, on which the disk 15 is mounted, and it will be seen that by turning the handle 18 the apertured disk can be firmly locked at the point to which it is adjusted by the fingers, thus preventing its accidental 75 movement while the punch is being operated.

It is thought that from the foregoing description, taken in connection with the accompanying drawings, the construction and operation of my new and improved watch-maker's punch will be readily understood 80 without requiring further description.

Having thus described my invention, what I claim, and desire to secure by Letters Patent, is—

1. In a watch-maker's punch, the combination of the integral lower jaw, slotted upper jaw and lower handle, the punch having the slotted upper end and the spiral spring for retracting the same, the centrally-pivoted lever 8, having the slotted inner end, and the pivoted handle 10, having the curved end 11, passing through the slotted inner end of the lever 8, substantially as set forth.

2. The combination, in a watch-maker's punch, of the integral lower jaw, the slotted upper jaw and lower handle, the punch 5, having the slotted upper end and retracting-spring 6, the centrally-pivoted lever 8, having the curved outer end and the slotted in-

- ner end provided with an anti-friction roller 9, and the pivoted handle 10, having the curved end 11, passing through the slotted inner end of the lever 8, substantially as set forth.
- 5 3. The combination of the lower jaw formed with the openings 12 and 13, the slotted upper jaw and the lower handle 3, the punch and the pivoted levers for operating the same, and the disk 15, formed with the series of openings 16 and the milled outer edge and mounted on the pivot-stem 14, substantially as set forth.
- 10 4. In a watch-maker's punch, the combination of the lower jaw formed with the open-

ings 12 and 13, the slotted upper jaw, the punch having the slotted upper end and the pivoted levers for operating the same, the apertured disk 15, mounted on the pivot-stem 14, and the clamp 17, having the adjusting-handle 18, substantially as set forth.

In testimony whereof I affix my signature in presence of two witnesses.

URIAH D. MINER.
